(57) **CLAIM**

The ornamental design for a solar cell, as shown and described.

DESCRIPTION

1. Solar cell

2. Solar cell

1.1 : Front

1.2 : Back

1.3 : Enlarged

2.1 : Front

2.2 : Back

2.3 : Enlarged

Description of the characteristic features of the design(s), or matter for which protection is not sought: Design 1 and 2 main design point: lies in the pattern; a view that best

(Continued)

A

illustrates the point of the design 1 and 2: front view; design 1 and 2 possible use: power generation; View omitted: the design product is a thin product, and the left view, right view, top view and bottom view of design 1-design 2 are omitted; The black box displaying "A" in replica 1.1 is the enlarged view shown in replica 1.3; The black box displaying "A" in replica 2.1 is the enlarged view shown in replica 2.3.
